UNITED STATES PATENT OFFICE

OLIVER C. RITZ WOLLER, OF CHICAGO, ILLINOIS

TREAD PLATE

Application filed December 17, 1928. Serial No. 326,425.

My invention relates to tread plates of the type comprising a mat furnishing the desired character of bearing surface, a metal plate on which said mat is mounted, and means for holding the mat in operative position. It is the object of my invention to provide a new and improved form and arrangement of parts in a device of this type whereby the device can be produced at a moderate cost in a form which will be acceptable from the standpoint of strength and stiffness, from the standpoint of length of life of the device, from the standpoint of ease of replacement of the mat in the combination, and from the standpoint of attractiveness of appearance of the completed device.

It is one of the objects of my invention to provide an improved tread plate of this type pivotally mounted in position for actuating the accelerator of a motor car whereby the pressure from the driver's foot can be applied effectively at any part of the plate without the necessity for accurate positioning of the foot at any particular point. It is one of the objects of my invention to provide an improved construction of tread plate of this kind by reason of which the mat may be readily withdrawn from the frame for replacement when desired.

It is another object of my invention to improve devices of this type in sundry details hereinafter pointed out. The preferred means by which I have accomplished my several objects are illustrated in the accompanying drawing and are hereinafter specifically described. That which I believe to be new and desire to cover by this application is set forth in the claim.

In the drawing,—

Fig. 1 is a top plan view of the preferred form of my improved device;

Figs. 2, 3 and 4 are vertical sectional views taken respectively at the lines 2—2, 3—3 and 4—4 of Fig. 1;

Fig. 5 is a view similar to Fig. 1 but showing a modified form of construction;

Figs. 6 and 7 are vertical sectional views taken respectively at the lines 6—6 and 7—7 of Fig. 5; and

Fig. 8 is a view similar to Fig. 2 but showing a modified form of construction.

Referring to Figs. 1 to 4 inclusive, in which corresponding parts are indicated by the same reference characters, 10 indicates a sheet metal plate of oblong shape, having strengthening ribs 11 pressed downwardly in its top face longitudinally of the plate, and having flange portions 12 and 13 at its sides and a flange portion 14 at one end extending upwardly and inwardly about the edges of a mat 15 positioned on the plate, such mat being preferably formed of rubber or similar material. In the construction shown, the mat 15 is provided with longitudinally extending ribs 16. The mat 15 is held in position by means of a cross bar 17 overlying one end of the mat 15 and held in position upon the plate 10 by means of screws 18.

In the form of device as shown in Figs. 1 to 4, I have provided means for connecting the tread plate in position for actuating the accelerator of an automobile, such means comprising a metal plate 19 hingedly connected with the end of the plate 10 adjacent to the plate 17 above referred to, the hinging means comprising sleeve portions formed integrally with the plates 10 and 19, connected together in the ordinary manner by means of a pintle 20. A coiled spring 21 is mounted on the pintle 20, having one end portion positioned in a groove 22 in the bottom face of the plate 19, and having its other end portion extending through a loop 23 pressed downwardly from the plate 10, the spring serving normally to press the plates 10 and 19 toward each other.

As is clearly shown in Fig. 1, the flange portions 12 and 13 are not only formed integrally with the bottom plate 10 but also with the end flange 14, such flange portions comprising a rim extending continuously about substantially the entire periphery of the device. At the point where the flanges 12 and 13 terminate at the pivoted end of the tread plate, the plate 17 is provided having its upper face flush with the upper faces of the flanges. In this manner a very neat appearance is provided. The plate 17 is re-

movable so as to enable the mat 15 to be drawn out for replacement when it becomes worn. By the provision of the strengthening ribs 11, and the provision of the turned flanges 12, 13 and 14 formed integrally about the greater part of the periphery of the plate, a very strong and stiff construction is assured. By the provision of the spring 21 for pressing the plate 10 toward the plate 19, the tread plate as a whole is kept in snug contact with the accelerator of the car so as to prevent rattling or displacement of the plate.

In the construction shown in Figs. 5, 6 and 15 7, a bottom plate 24 is employed, reenforced by strengthening ribs 25 corresponding with the ribs 11 of the construction first described. The plate 24 is connected to a second plate, in the construction shown, in precisely the same manner as that above described, and the parts are accordingly designated by the same reference characters.

In the construction shown in Figs. 5, 6 and 7, a mat 15 is employed, held in position by 25 metal rim means which extends downwardly and inwardly about the edge of the mat for holding the mat in position on the plate. In the construction here shown, a metal rim 26 is employed formed separately from the 30 plate 24, such rim having its horizontal flange portions formed integrally with each other about the entire periphery of the device, as is clearly shown in Fig. 5. The rim 26 is 35 preferably in the form of a sheet of aluminum or other comparatively soft metal cut out at its middle portion for receiving the ribs 16 of the mat therethrough, and having its outer edge portion turned downwardly and inwardly about the edge portions of the 40 mat 15 and the plate 24.

In the construction shown in Fig. 8, still another form of device is shown, comprising a bottom plate 27 similar to the bottom plate 10 and accordingly being given corresponding reference numerals. In the construction here shown a rim member 28 similar to the rim member 26 of the construction shown in Figs. 5, 6 and 7 is employed, such rim member 28 extending downwardly and inwardly about the edge portions of the mat 15 and the bottom plate 27 for reenforcing the construction and for improving the appearance of the device.

While I have designed my improved tread plate particularly for use in connection with the accelerator of an automobile, it is to be understood that the invention is not limited to such use. Moreover, the invention is not to be limited with respect to any of the details of construction except so far as the claim is so limited by reference to the prior art.

I claim:—

A device of the class described, comprising in combination a sheet metal bottom plate, a mat on said plate, metal rim means extending upwardly and inwardly about the edge of the mat for holding the mat in position on the plate, a second plate hingedly connected with said first named plate at one end thereof, and a coiled spring mounted on the pintle of the hinge, with one end portion engaging a groove in the bottom face of said second plate and with the other end portion extending through a loop carried by said first named plate for pressing said plates yieldingly toward each other.
